UNITED STATES PATENT OFFICE.

JOHN H. GRAYSON, OF ATHENS, OHIO.

BURNER TIP.

Application filed September 23, 1922. Serial No. 590,161.

To all whom it may concern:

Be it known that I, JOHN H. GRAYSON, a citizen of the United States, residing at Athens, in the county of Athens and State of Ohio, have invented certain new and useful Improvements in Burner Tips, of which the following is a specification.

This invention relates to burner tips of the type used for burning gaseous fuel.

10 It is the general object of the invention to provide a burner tip which is efficient in operation and can be cheaply manufactured.

For a full understanding of the invention reference is had to the accompanying drawings in which

Fig. 1 is a plan view of a device embodying the invention;

Fig. 2 is an elevation thereof;

Fig. 3 is a vertical section;

20 Fig. 4 is a plan view of a modification of the device shown in Figs. 1-3;

Fig. 5 is an elevation thereof; and

Fig. 6 is a sectional view showing a detail.

25 The principal part of the tip is an element 10 of cast iron or other suitable cheap refractory material.

As indicated in Fig. 3 this element 10 may have a lower ring portion 10^a and an upper portion 10^b provided with parallel slots 10^c. The element 10 is manufactured by casting and subsequently sawing the slots. The portion 10^b is cast solid and the ring portion 10^a defines a hollow space below the cylindrical portion. When saw cuts are made, the resulting slots 10^c are in communication with the hollow space mentioned.

The element 10 is surrounded by a ferrule 12 of brass or other suitable material. This ferrule, in its more specific aspect, has a threefold purpose: It provides a ring portion 12^a enclosing the cylindrical portion 10^b and thereby preventing the lateral issue of the gas. The portions of the ring portion contiguous to the slots 10^c are deflected inwardly and thereby form strengthening braces 12^b for the bars 10^d resulting from the saw cuts. The lower portion 12^b of the ferrule affords a means for attaching the tip to the burner.

It is readily understood that a part of the thermal effect of the flame is lost if the flame is permitted to project laterally following the path of least resistance, especially in connection with radiant mantles of

the tubular refractory glower type. It may be remarked also, that the lateral issue of the flame would cause a popping noise striking the sides of the tubular glower.

60 The provision of the braces between the bars 10^d is of considerable advantage, inasmuch as the bars of cheap cast iron or other cheap material, have comparatively little resistivity against breaking. If somebody should place a knife or other similar instrument in a slot with a view of facilitating removal, the bars are sufficiently braced to withstand breakage. At the same time the deflection of the ferrule material into the 70 slots provides a rough or knurled surface for applying turning force.

65 The depending portion 12^b may be provided with screw threads for attaching it to the burner but I prefer to use the well known bayonet slot construction. The bayonet slot 12^e may co-operate in the usual manner with a pin or similar projection 13 on the inner wall of the burner portion 14 to which the tip is applied. The tip may 80 thus be quickly put in place by an axial movement followed by a short rotary movement and may be as readily detached. When in operative position, the tip is securely held against being blown out by a 85 flash-back in the burner.

75 The ferrule may be prevented from slipping relatively to the element 10 by indentures defining small protuberances 12^d or the like.

90 As shown in Figs. 1, 2, 3 and 6, the ring portion 10^a may project outwardly to form a shoulder to positively prevent relative movement between the casting and the ferrule in one direction and at the same time 95 to strengthen the ring portion. However, the casting 10^b, may be made cylindrical throughout, as shown in Figs. 4 and 5, to cheapen the manufacture thereof. The frictional contact between the braces or tongues 100 of the ferrule and the bars 10^d, may be made sufficient to prevent relative movement.

I am aware that slotted burner tips are broadly not new.

I claim:

105 1. A burner tip comprising an element having as an integral construction a lower ring portion and an upper portion defining a plurality of parallel bars and resulting slots, and a ferrule surrounding the upper 110 portion, parts of the ferrule extending into the slots and providing braces for the bars.

2. A burner tip comprising an element having as an integral construction a lower portion defining a gas passage and an upper portion defining a plurality of parallel bars and resulting slots, and a ferrule surrounding the said element, parts of the ferrule extending into the said slots and a portion of the ferrule extending below the lower portion of said element and providing means for attachment to a burner.
3. A burner tip comprising an element having as an integral construction an upper portion defining a plurality of parallel bars and resulting slots and a lower ring portion whose outside diameter is different from that of the upper portion, and a ferrule having an upper portion surrounding the said portion and having parts extending slightly into the lateral ends of the slots and having a lower portion extending below the said ring portion and providing means for attachment to a burner.
4. A burner tip comprising an element having as an integral construction a lower ring portion and an upper portion defining a plurality of parallel bars and resulting slots and a ferrule surrounding the said element, portions of the ferrule entering the slots and forming braces for the bars, the lower portion extending below the element and affording connection to a burner.

In testimony whereof, I affix my signature.

JOHN H. GRAYSON.
